United States Patent Office.

JAMES GRANGER, OF ZANESVILLE, OHIO.

Letters Patent No. 64,309, dated April 30, 1867.

BOAT-BUILDERS' PLATFORM.

The Schedule referred to in these Letters Patent and making part of the same.

TO ALL WHOM IT MAY CONCERN:

Be it known that I, JAMES GRANGER, of Zanesville, in the county of Muskingum, and State of Ohio, have invented a new and useful improvement in Boat-Builders' Platform; and I do hereby declare that the following is a full, clear, and exact description thereof, which will enable others skilled in the art to make and use the same, reference being had to the accompanying drawings, forming part of this specification, in which—

Figure 1 is a top or plan view of my improved platform.

Figure 2 is a vertical cross-section of the same, taken through the line $x x$, fig. 1, and showing in red lines a boat in position upon it.

Figure 3 is the same view as fig. 2, showing the platform inclined for launching the boat, and the boat launched.

Similar letters of reference indicate like parts.

My invention has for its object to furnish an improved platform, by means of which flatboats and other vessels may be conveniently built bottom upwards, and from which they may be easily launched. And it consists of an improved platform, formed by the combination of cross-beams, longitudinal timbers, strengthening pieces and posts, with each other, in the manner hereinafter more fully described.

A are the posts upon which the platform rests, and which extend about three and a half feet above the ground when the ground has a sufficient inclination from the water. But when the ground is level, the proper inclination may be obtained by building an artificial foundation for the platform, as represented in the drawings, or by lengthening the posts A, and strengthening them accordingly. The dimensions given in this description are merely suggested proportional dimensions, the actual size of the platform depending upon the character of the vessels for building which the platform is intended to be used. Upon the tops of the posts A are formed tenons, the tops of which are rounded off, and their shoulders inclined, so as to allow the platform to be tipped into the position shown in fig. 3, for convenience in launching the vessel. The cross-timbers B are about twenty-four feet long, and are strengthened in their main bearings by pieces of wood D, which are about six feet in length, and of the same width as the cross-timbers B, to the under side of which they are attached. In or through these pieces D are made mortises, into which fit the tenons formed upon the upper ends of the posts A, upon which the cross-timbers rest, as before described. The posts A and cross-timbers B should be placed about eight feet apart. E is a round timber, securely attached to the ends of the cross-timbers B, that rest upon the ground when the platform is in a horizontal position. F are longitudinal timbers, attached to the under sides of the cross-timbers B, to connect and strengthen them. These timbers F are placed beneath the timbers B, to be out of the way when launching the vessel. The platform may be secured in a horizontal position while building the vessel, in any convenient manner.

The vessel is launched by tipping the platform into the position shown in fig. 3, and allowing the vessel to slide down the timbers B, its descent being regulated by ropes attached to the side-timbers of the boat on the side towards the water. These ropes then pass under the boat, and pass around the round timber E. Upon reaching the water the vessel may be turned over by the ordinary means in the hands of every flatboat builder. The side of the boat that sustains the weight while being turned over should be strengthened for the occasion with additional braces.

I claim as new, and desire to secure by Letters Patent—

1. Pivoting the tilting platform to the post A, so that, when the platform is tilted, the entire weight of the platform and the boat will rest upon the foundation, or directly upon the ground, substantially as described, for the purpose specified.

2. The post A, with its inclined shoulders, to which the platform B is pivoted, at a distance nearer to its inner end than at its outer, so that, when the platform is lowered, the weight is upon the ground or the foundation, in the manner as and for the purpose specified.

JAMES GRANGER.
